UNITED STATES PATENT OFFICE

2,417,297

BELL

Alfred R. Euler, New York, N. Y.

Application April 7, 1945, Serial No. 587,159

4 Claims. (Cl. 116—154)

1

This invention relates to improvements in bells and, more specifically, to a new and improved rotary bell which is well adapted for various purposes such as burglar alarms, bicycle bells, store bells and the like.

The term "rotary bell" usually defines a bell which is actuated by rotation of a handle or a wheel, or the like, as distinguished from bells that are actuated by a reciprocating motion of a handle, of a push button, or the like. The use of rotary bells has been limited due to the fact that the hitherto known bells of this type produce a sound only when their rotating parts are turned at a comparatively high speed, and due to the fact that the hitherto known rotary bells are complicated, expensive and more subjected to wear and tear than other types of bells. Therefore, the primary object of the present invention is the provision of a device of the character described which reliably will produce a clear sound irrespective of the speed by which it is actuated, and which particularly will produce the sound even if it is actuated at a slow-motion speed.

Another object of the present invention is the provision of a device of the character described which can be installed easily on windows, doors, drawers of cash registers, and the like, and which will produce the desired sound if it is turned in a clockwise as well as in an anti-clockwise direction.

Still another object of the present invention is the provision of a device of the character described which is closed all around in such a manner that it will permit practically no access of dust, humidity and the like to its mechanism.

Yet still another object of the present invention is the provision of a device of the character described which is simple in construction and inexpensive to manufacture, but reliable in operation and well adapted to withstand the rough usage to which such devices are ordinarily subjected.

Further objects of the instant invention reside in any novel combination of parts present in the embodiment of the invention described and shown in the accompanying drawing, whether within or without the scope of the appended claims and irrespective of other specific statements as to the scope of the invention contained herein.

In the drawing:

Figure 1 is a side elevation of a preferred embodiment of my invention as it appears when

2

it is used as a burglar alarm in connection with a sliding window;

Figure 2 is a top plan view of the device as it appears after the removal of the bell cup;

Figure 3 is a sectional view on the line 3—3 of Fig. 2; and

Figure 4 is a top plan view of the device as it appears after the removal of the bell cup, showing a slight modification of a detail.

Similar numerals refer to similar parts throughout the several views.

In Figs. 1 to 3 the numeral 1 denotes my improved rotating bell, which may be held in place by any suitable means, and which in the instance shown in Fig. 1 is attached to the stationary part of a window frame 4 by means of angular members 2 and 3. The device 1 is carried by a resilient member, preferably by a flat spring 5, which is attached to part 2 by means of rivets or the like that are extended through holes 6 in spring 5. The spring 5 presses the device 1 against the movable window part 7 in such a manner that the rotatable disk 8, whose rim rests against the part 7, will be rotated if the window is slid up or down. I prefer to provide the outer side of the rim of disk 8 with a roughage 9, so that even a slight pressure of spring 5 will be sufficient for rotating the disk 8 when the window is opened or closed. The parts 4 and 7 of the window are shown as being partially broken away in Fig. 1.

The disk 8 is rotatably carried by a shaft 12 and is located between the vertical portion 11 of a bearing bracket and a cross-bar 13 which is non-rotatably secured to shaft 12. The horizontal portion 10 of the bearing bracket is secured to the spring 5, and the shaft 12 is stationary and is secured to the vertical portion 11. A circular row of pins 14 extends perpendicularly from one side of disk 8, and the pins 14 are in spaced relation to one another, as may be seen in Figs. 2 and 3. While the pins 14 can be attached to the disk 8 in any suitable manner, I prefer to form them as a unit with disk 8 or to stamp them out of disk 8 and bend them rectangularly to the surface of the disk 8, so that there will be slots 15 in disk 8 as shown in Figs. 2 and 4. The pins 14 are arranged in such a manner that they engage tiltable members, which are pointed tongues 16 and 17 in the instance shown in Figs. 2 and 3. The tongue 16 is pivotally attached to the portion 19 of a curved arm, and the tongue 17 is pivotally attached to portion 20 of another curved arm. One of these arms is pivoted to each extremity of the stationary cross-bar 13 at

23, and pins 18 are arranged near the tongues 16 and 17 respectively for the purpose of limiting the tilting movement of the tongues 16 and 17. Springs 21 and 22 are provided on the arm portions 19 and 20 respectively and engage the cross-bar 13 in such a manner that they bias the portions 19 and 20 toward the pins 14. From the arrangement of the parts 14 to 23 just described it will be obvious that, upon rotation of the disk 8 in either direction, the tongues 16 and 17 in cooperation with the pins 14 and 18 and the springs 21 and 22 will cause an oscillating tilting movement of the arms, so that the hammers 26, which are on the arm portions 25, will strike against a bell cup 27 each time when the springs 21 and 22 swing the arms around the pivots 23 in a clockwise direction. In Fig. 2 the arm portion 20 is shown in a position in which the hammer 26 strikes or just has struck, while the arm portion 19 is in a position just before the striking of the hammer. The bell cup 27 is carried preferably by the outer extremity of the stationary shaft 12 (Fig. 3), and its lower periphery is surrounded by the rim of disk 8, so that there will be but a small open space between the edge of the cup 27 and the disk 8. This will, to a considerable extent, protect the clock mechanism against dust, humidity and the like, because the parts 13 to 26 inclusive are substantially enclosed and protected by the cup 27 and the disk 8. That portion of the stationary cross-bar 13 which is adjacent the disk 8 is provided with recesses 28 (Fig. 3) through which the pins 14 travel when the disk 8 is rotated. The arm portions 25 are recessed at 24 (Fig. 2) in such a manner that the recessed portions 24 will rest against the cross-bar 13 when the springs 21 or 22 swing the arm portions 25 outwardly and when the cup 27 is removed, so that the tilting movement of the arms is limited and that a hitting of the portions 19 and 20 upon the pins 14 will be prevented.

The purpose of the tiltable tongues 16 and 17 is to assure a proper hitting movement of the hammers and a sounding of the bell irrespective of the speed by and the direction in which the disk 8 is rotated.

According to the modification of Fig. 4, only the tiltable two prongs fork 30 is substituted for the pointed tongues 16 and 17. The fork 30 is pivoted to the arm at 31, and its movement relative to the arm is limited at one side by a pin 33 and at the other side by a pin 32. The pins 32 and 33 are secured to the arm, and pin 32 can be utilized as support for the spring 22. The arm portion 35 and the hammer 36 are identical to the portion 25 and to hammer 26 respectively of Figs. 2 and 3.

Although I have illustrated my invention in the particular form shown in the drawing, it is to be understood that I contemplate constructing it in various ways and therefore I do not desire to be limited to the exact structure as shown but aim to cover all that which comes within the spirit and scope of the appended claims.

Having described my invention, what I claim as new and desire to secure by United States Letters Patent is:

1. A rotary bell comprising a resilient member, a bearing bracket carried by said resilient member, a shaft non-rotatably secured to said bracket, a disk rotatably attached to said shaft and having on one side a circular row of pins laterally extending therefrom, a cross-bar non-rotatably attached to said shaft in such a manner that said

disk is located between said bracket and said cross-bar, a curved arm pivotally secured to the extremity of said cross-bar and having a hammer head at one end portion and a tiltable member at its other end portion, means for biasing the arm portion which carries said tiltable member towards said circular row of pins, and a bell cup secured to the outer extremity of said shaft, said disk protruding over the outer periphery of said bell cup, and said tiltable member engaging said row of pins in such a manner that said arm will be oscillated on the pivot of said cross-bar when said disk is rotated, all substantially as set forth.

15 2. A rotary bell comprising a resilient member, a bearing bracket carried by said resilient member, a shaft non-rotatably secured to said bracket, a bell cup secured to the outer extremity of said shaft, a cross-bar within said bell cup being non-rotatably attached to said shaft, a disk between said bracket and said cross-bar being rotatably attached to said shaft and having on one side a circular row of pins laterally protruding therefrom, a pivot being provided at each end portion of said cross-bar, curved arms each of which having its center portion tiltably attached to one of said pivots and having a hammer head at one end portion and a tiltable member at its other end portion, and means for biasing that portion of each arm which carries said tiltable member towards said circular row of pins, said disk protruding over the outer periphery of said bell cup, and said tiltable member on each arm engaging said row of pins in such a manner that said arm will be oscillated on the pivot of said cross-bar when said disk is rotated, all substantially as described.

30 3. A rotary bell comprising a resilient member, a bearing bracket carried by said resilient member, a shaft non-rotatably secured to said bracket, a bell cup secured to the outer extremity of said shaft, a cross-bar within said bell cup being non-rotatably attached to said shaft, a disk between said bracket and said cross-bar being rotatably attached to said shaft and having on one side a circular row of pins laterally protruding therefrom, a pivot being provided at each end portion of said cross-bar, curved arms each of which having its center portion tiltably attached to one of said pivots and having a hammer head at one end portion and a tiltable tongue at its other end portion, and a spring on each arm for biasing its portion which carries said tiltable tongue towards said circular row of pins, said disk protruding over the outer periphery of said bell cup, and said tiltable tongue on each arm engaging said row of pins in such a manner that said arm will be oscillated on the pivot of said cross-bar when said disk is rotated, all substantially as described.

35 4. A rotary bell comprising a resilient member, a bearing bracket carried by said resilient member, a shaft non-rotatably secured to said bracket, a disk rotatably attached to said shaft and having on one side a circular row of pins laterally extending therefrom, a cross-bar non-rotatably attached to said shaft in such a manner that said disk is located between said bracket and said cross-bar, a curved arm pivotally secured to the extremity of said cross-bar and having a hammer head at one end portion and a tiltable two-prong fork at its other end portion, a spring for biasing the arm portion which carries said tiltable fork towards said circular row of pins,

and a bell cup secured to the outer extremity of said shaft, said disk protruding over the outer periphery of said bell cup, and the prongs of said tiltable fork engaging said row of pins in such a manner that said arm will be oscillated on the pivot of said cross-bar when said disk is rotated, all substantially as described.
